DESIGN FOR A BALL COCK

Alfred C. Arbogast, Elkhart, Ind., assignor to Northern Indiana Brass Company, Elkhart,
Ind.

Application December 6, 1937, Serial No. 73,388

Term of patent 14 years

To all whom it may concern:

Be it known that I, Alfred C. Arbogast, a citizen of the United States, residing at Elkhart, in the county of Elkhart and State of Indiana, have invented a new, original, and ornamental Design for a Ball Cock, of which the following is a specification, reference being had to the accompanying drawing, forming part thereof, in which:

Fig. 1 is a front elevation,

Fig. 2 is a side elevation looking from the right of Fig. 1,

Fig. 3 is a side elevation partially broken away looking from the left of Fig. 1, and

Fig. 4 is a top plan view of a ball cock, showing my new design.

I claim:

The ornamental design for a ball cock, as shown.

ALFRED C. ARBOGAST.
